(57) **CLAIM**

The ornamental design for a display panel with a graphical user interface, as shown and described.

DESCRIPTION

FIG. 1 is a front view of a display panel with a graphical user interface showing a first embodiment of our design; FIG. 2 is a front view of a display panel with a graphical user interface showing a second embodiment thereof; and FIG. 3 is a front view of a display panel with a graphical user interface showing a third embodiment thereof. The broken lines, including all text, illustrate portions of the graphical user interface or mixed reality environment and form no part of the design.
